J. N. POWERS.
SALES BOOK.
APPLICATION FILED AUG. 6, 1921.

Patented Aug. 15, 1922.

UNITED STATES PATENT OFFICE.

JOHN N. POWERS, OF WASHINGTON, DISTRICT OF COLUMBIA.

SALES BOOK.

1,425,690.

Specification of Letters Patent. Patented Aug. 15, 1922.

Application filed August 6, 1921. Serial No. 490,334.

To all whom it may concern:

Be it known that I, JOHN N. POWERS, a citizen of the United States, and resident of Washington, in the District of Columbia, 5 have invented certain new and useful Improvements in Sales Books, of which the following is a specification.

My invention relates to manifold sales books particularly of the triplicate record 10 type, that is, of the type in which the record sheets are divided by weakened lines into three sections designed to be folded into superimposed relation with transfer sheets between them, whereby the desired original 15 and two copies of any given transaction may be recorded, and it is my purpose to provide improvements in such books whereby the number of operations necessary to structurally produce the same are reduced to a 20 minimum and whereby the production cost is as a result correspondingly lowered.

More specifically my invention consists in cutting the upper ends of the record sheets along a straight line diagonal with respect 25 to their vertical edges so that as previously mentioned, the books are cheap and easy to produce while at the same time the respective sections are readily foldable one upon the other in a desired manner and in other 30 respects are capable of quick and easy manipulation.

With the foregoing and other purposes in view, my invention consists in the novel features of construction and relative arrangements as will be hereinafter more fully explained, illustrated in the accompanying drawings, and claimed.

In the drawings wherein like characters of reference denote corresponding parts in the 40 different views:—

Fig. 1, is a perspective of a sales book embodying the novel and essential characteristics of my invention, one of the foldable sheet sections being shown in extended position in dotted lines and the carbon sheets being shown extended to more clearly illustrate the arrangement.

Fig. 2, a view similar to Fig. 1 showing the manner of folding the record sheet sections and the carbon sheets preparatory to recording a transaction.

Fig. 3 a front view showing more clearly the manner of diagonally cutting the upper ends of the sheets; and

Fig. 4, an enlarged fragment of one of the 55 record sections showing the arrangement of figures thereon representing different values and adapted to be crossed out to indicate the amount involved in any given 60 transaction.

Referring to the drawings in detail, it will be observed that I have illustrated my improved sales book as embodying the usual record sheets, carbon or transfer sheets for insertion between the respective sections of 65 the record sheets when the latter are folded, and a cover to which the record and transfer sheets are secured or attached.

This constitutes my sales book in its complete and preferred embodiment as the elements thereof are relatively permanently associated and the book as an entirety is strong, durable, convenient to use and of attractive appearance. My improvements, however, are directed solely to the record 75 sheets which in themselves constitute a sales book capable of use with or without a cover and with transfer sheets either loose or permanently associated therewith in any preferred manner, irrespective of whether a 80 cover is or is not provided.

The record sheets 10 are divided by one or more weakened vertical lines 11 into record sections of any desired number, three being shown in the present instance designated from left to right *a*, *b*, and *c*, respectively. These sections are adapted to be folded in superimposed relation with carbon sheets between them whereby two copies in addition to an original record of any given 85 transaction may be produced. First, a transfer sheet 12 is placed upon section *a*. Section *b* is then folded over upon section *a* and the transfer sheet and a second transfer sheet 13 is then placed upon that side 90 of section *b* which was originally its rear face. Finally section *c* is folded upon section *b* and the second transfer sheet with the final result illustrated in Fig. 2. Section *c* as a consequence is disposed uppermost and constitutes the original record section, while sheets *b* and *a* respectively con-

stitute the first and second copy sections. Sections *b* and *c* are adapted to be separated from section *a* and from each other along the weakened lines as is understood.

5 I am aware that sales books having record sheets of the type mentioned designed to be folded in the manner indicated and subsequently separated have been produced heretofore, but they have not come into more 10 general use principally because of the comparatively excessive cost of their production, for provision must be made to avoid interference between the respective sections during folding and heretofore this has required 15 separate cutting operations upon the sheets in such manner that only relatively small numbers of the same could be produced at one operation.

In Fig. 3 of the drawings the light lines 20 14 indicate approximately the original condition of the sheets before being cut either as heretofore or in accordance with my present improvements whereby sections *b* and *c* may be folded upon each other and 25 upon section *a* without interference by the latter sections. The manner of cutting the sheets heretofore is indicated by the dotted lines 15—16 from which it is apparent that 30 separate cuts are necessary and due to the relative angularity of the same it is further apparent that only small numbers of sheets 35 may be cut at one operation. I eliminate these disadvantages and as a result reduce the cost of manufacture by cutting the upper 40 ends of the sheets at an angle with respect to their side edges as indicated in each of the views at 17. The degree of angularity of this cut may be varied within maximum 45 limits, but preferably it will be sufficiently great to permit free folding of the sections without interference one with the other and sufficiently slight to avoid the unnecessary wastage of paper. Preferably I begin this angular cut at a point approximately mid-way 50 between the vertical sides of the sections *a* and cut in a straight line downwardly and outwardly towards section *c*.

The binding for the sheets whereby they are secured together in pad form is located 55 at the upper end of the section *a* and extends from the left hand edges of the sheets only as far as the point at which the cut 17 begins. The sections *a*, therefor, after sections *b* and *c* have been severed therefrom, and upon 60 being turned back as indicated at 18 in Fig. 1 are capable of relatively great lateral movement without tearing which is a result of the flexibility produced by the manner of cutting and binding specified and 65 which is desirable in the use of the book as the tendency of the sections *a* to turn back and assume their flat pad form is to a large extent eliminated.

As previously intimated my improvement 70 consisting in angularly cutting the upper

edges of the sheets is equally applicable to record sheets having a greater or less number of record sections than the three sections herein illustrated and regardless of the number of sections to each sheet the same 70 may be arranged in perfectly flat pad form or they may be initially folded as indicated in Fig. 1 to reduce the lateral dimension of the book. In other words sections *b* and *c* may be initially folded, the latter under the 75 former, so that it is only necessary to turn section *b* over upon section *a* whereupon section *c* will be disposed in proper folded relation to section *b* and all that is necessary 80 is to insert a transfer sheet between said sections.

In association with the record sheets I have provided means to assist in determining the correct amount of sums of money indistinctly or carelessly written on said sheets. 85 This means consists of two rows of figures arranged in any preferred manner on the respective sections and respectively indicating dollars and cents whereby a clerk by crossing out certain of these numbers may 90 indicate the exact amount of any particular sale or transaction. For instance, if a sale amounted to four dollars and thirty cents the numeral four (4) in the dollars column and the numeral thirty (30) in the cents column 95 would be crossed out and so on, and the cashier or person making change would know exactly the amount of the transaction whether the clerk's record was or was not distinct. Each sheet is provided with the 100 columns of figures mentioned and these columns are so arranged that they lie directly over one another when the sections are folded, whereby the figures of each section are crossed out in a corresponding manner. 105

I claim:

1. A manifold sales book comprising record sheets divided into sections adapted to be folded into superimposed relation, corresponding edges of the respective sheets being 110 cut at an angle with respect to their direction of fold, said angular cut extending in a straight line through all of the sections when the latter are in unfolded relation.

2. In a manifold sales book, a record 115 sheet divided into sections adapted to be folded into superimposed relation, an edge of said sheet being cut at an angle to the direction of fold of the sections thereof, said cut extending in a straight line through all 120 of the sections when the latter are in unfolded relation.

3. In a manifold sales book, a record sheet divided by weakened lines into record sections adapted to be folded into superimposed 125 relation, an edge of said sheet being cut at an angle to the direction of fold, said cut being straight and continuing through each record section when the latter are in unfolded relation. 130

4. A manifold sales book comprising record sheets divided into sections adapted to be folded into superimposed relation, means binding said sheets together, said means extending throughout only a portion of the extent of one edge of a single record section, the remaining edge portion of the same section and adjacent edges of the other sections being cut at an angle to the direction of fold. 10
- 5 In testimony whereof I hereunto affix my signature.

JOHN N. POWERS.
